PNEUMATICALLY OPERATED
FLOATING DRY DOCK
Harold Roberts, 3600 21st St.,

Filed Oct. 24, 1965, Ser. No. 504,538
8 Claims. (Cl. 114—45)

This invention relates to a floating dry dock and, more particularly, to a dry dock which may be submerged below the surface of the water by taking in water as ballast and then being refloated to the surface under a vessel which is to be serviced by means of displacing the water ballast with compressed air.

I am familiar with a variety of prior art floating dry docks which utilize water as ballast to submerge temporarily and then discharge the water ballast to ascend back to the surface. Such facilities generally are provided with airtight ballast containers of substantially rigid construction, and ballast control is usually achieved by directing compressed air at certain rates and pressures into the water compartments to expel the water ballast. The rigid ballast compartments impose a substantial displacing volume which must be overcome by a certain fixed amount of ballast before the dock may be submerged and are of a relatively costly construction. When the dock is resurfaced, at least a portion of such additional ballast normally must be expelled by the use of compressed air, thus adding load to the compressed air system. Since it is usually desirable to surface a dry dock as rapidly as is practicable, the compressor should have a capacity sufficient to evacuate the water ballast from all tanks within a relatively short time period. The initial pressure against which the compressor must work, therefore, dictates its maximum pressure capacity at whatever rate of cubic foot displacement is necessary for a particular application. The size of compressor required, i.e. its power rating, is generally a function of the aforementioned maximum pressure capacity and the time period that such pressure must be delivered. Hence, the longer the time that a submerged dock remains on the bottom during ballast discharge, the larger must be its compressor.

It is an object of this invention to provide a submergeable floating dock which may be submerged and refloated relatively rapidly using a minimum of ballast and requiring a relatively limited amount of compressed air at moderate pressures.

More specifically, it is an object to provide a floating dock having at least one rigid ballast compartment and a pneumatically inflatable bag secured to the underside of the dock platform. When the dock is to be submerged, the inflatable bag is depressed to its flat deflated condition, and the rigid ballast compartment is opened to take in water. The volumetric relationship of the entire dock structure to be submerged and the volume of the ballast compartment is selected so the dock submerges when the compartment is filled with water. The dock is refloated by first blowing the water from the ballast compartment by means of compressed air and then conveying air to the pneumatically inflatable bag from the ballast compartment by interconnecting pipes and valving. The rigid compartment and inflatable bag may be selected to provide positive buoyancy to the entire dock structure after equalization of pressure between the bag and ballast compartment, i.e. the volume of dock structure, ballast compartment and inflated bag is at least as great as the volume of water equal in weight to the entire dock structure.

A feature and an advantage of my invention is that once positive buoyancy is achieved by the equalization of pressure between the ballast compartment and the inflatable bag, the entire dock structure begins to ascend and

2

the flexible inflatable bag will continue to expand due to the decrease in surrounding hydrostatic pressure. Such continued expansion of the bag will accelerate the speed of ascent of the dock and continue to impart to it increased positive buoyancy, which is not possible using the wholly rigid tank designs of the prior art devices known to me. By proper selection of rigid ballast compartment and inflatable bag, the positive buoyancy of the dock structure once at the surface may be sufficient to support the vessel to be serviced with associated equipment and personnel, even without additional compressed air delivery to the inflatable bag.

Another feature and advantage of my invention is that the inflatable bag may be positioned above the rigid ballast tank which also acts as a receiver for air to be transferred to the bag when the dock is to be surfaced. With the bag positioned above ballast tank, the hydrostatic pressure at the elevation of the bag is always less than at the tank and the pressure of compressed air that may be received by the tank to evacuate water from it. Because of the relatively higher pressure of air in the ballast tank, positive buoyancy may be provided to the dock structure by transfer of air from the rigid ballast tank to the inflatable bag without the necessity of charging the rigid tank, now used as a receiver, to an even higher air pressure. Once positive buoyancy is imparted to the system, the higher elevation of the bag over the rigid tank accentuates the acceleration of the system to the surface.

Another object of this invention is to provide a floating dry dock of the type described above and wherein the rigid ballast compartment is comprised of a series of rigid pipe segments in fluid communication with one another.

Another feature and an advantage of this invention is that a major portion of the compartments necessary to receive air and provide positive buoyancy for refloating is provided in the form of a collapsible structure, i.e. the inflatable bag or bags. In this way the volume of dock structure that is displaced during submergence is made as small as possible, and the amount of ballast which must be taken in to submerge the dock, and expelled to refloat it, is minimized.

A further feature and advantage is that the inflatable bag or bags may be fabricated of rubber, polyethylene, or other suitable collapsible, relatively watertight material which may be easily handled and are relatively inexpensive.

Another feature and advantage of this invention is that a vessel may be positioned over the submerged dock while an air compressor expels at least a portion of the water from the rigid pipe segments. When complete refloating is desired, any remaining water may be expelled from the rigid pipe segments in a relatively short time.

Another feature and advantage of this invention is that the rigid pipe segments may be used as receiver tanks for the inflatable bag which has been in its deflated condition during submergence of the dock. Additional positive buoyancy may be imparted to the dock by transferring air from such receiver tanks to the inflatable bag without further work on the part of the air compressor, and the dock caused to continue to rise with increasing buoyancy during the rise due to expansion of the bag. This may be achieved by further inflating the rubber bag which is then at a water depth which requires less pressure for further inflation, and during ascent the air already present in the pipe segments and inflatable bag may continue to expand. The partial inflation of the inflatable bag, or bags, by the rigid pipe segments acting as a compressed air receiver for the bag distributes the compressor workload over a longer time period and at a lower average pressure than would normally be possible if the entire ballast system were of rigid

pipe construction. Thus a relatively smaller compressor may be used in my invention to refloat a given dock and vessel load within a predetermined total time interval than would normally be the case using all rigid construction ballast tanks.

Another object of this invention is to provide a floating dry dock of the type described above having rigid pipe segments in addition to those necessary for the water ballast. Such additional pipe segments may be of the ballast type and provide an added degree of stability to the unit during all stages of operation. If such segments are of the ballast type, i.e. provided with means for taking in and discharging water ballast, they may be used to maintain the dock in trim to prevent undue pitching or listing particularly during submergence and refloating.

Another object of this invention is to provide a dry dock of the type described above having at least a pair of spuds or pipe guides on either side of the dock. The pipe guides may be anchored to the ground bottom under the water in which the dock operates and engage the dock through suitable sliding guides.

The advantage of the aforementioned spuds is that the dock is provided with positive means of maintaining proper trim during submergence and refloating. The guides may also be provided with locks to maintain the dock in its elevated position during extended periods of vessel repair or maintenance without having to rely upon maintaining air in the rigid pipe segments or inflatable bag. Moreover, the compressed air source and piping may then be disconnected and used on other docks.

Numerous other objects, features and advantages will become apparent to one of ordinary skill in the art upon a reading of the specification which follows and by making reference to the accompanying drawing.

Turning now to the drawing, I show an isometric view of the dry dock embodying my invention with the top planking and structure shown partly fragmented to reveal certain details thereunder; the associated conventional compressor assembly and piping generally are shown schematically.

My invention is best understood by referring to the drawing which shows a dock at A in its floating condition with a vessel indicated at B supported thereon by several braces such as the one shown at C. The platform portion of the dock indicated at D may be fabricated from a variety of suitable materials using known construction techniques, and in the example shown a series of wooden planks 11 are joined together and supported between the bosoms of I beams 12. Enclosed, hollow, longitudinal pipes 13a are secured under longitudinal edge 14a of the platform on one side thereof and a similar series of pipes 13b are secured under opposite edge 14b. Although various lengths of docks may be accommodated by my invention, in the particular example shown three standard lengths of pipe are indicated joined by couplings 16b between pipes 13b, and similar couplings (not shown) may be used to join pipes 13a. The pipes themselves may be of a suitable standard stock product as provided capable of resisting the hydrostatic pressures imposed during operation. The pipe material should be selected to be either non-corrosive or provided with a corrosion-resistant protective layer. Couplings 16b may be of a simple sleeve type, and I have found it desirable to use ordinary rubber couplings which also give an added degree of flexibility in the longitudinal direction of the dock. Nonetheless, it may be desirable to reinforce the connected pipe sections and add longitudinal stiffness to the dock structure by providing elongate reinforcing ribs 20a and 20b under pipes 13a and 13b, respectively. Such members may be fabricated from wood or the like, and, together with curved straps 17a and 17b around portions of pipes 13 secured by means

of conventional fasteners to the underside of crossbeams 12, secure the pipes to the underside of the dock platform structure. The connection of straps 17a and 17b underneath the pipes to members 20a and 20b, respectively, may be accomplished by means of long, continuous, lateral crossrods 18 which give additional lateral stiffness to the dock structure.

Ballast tanks 19a and 19b, which may be of construction similar to pipes 13a and 13b respectively described above, are secured by means of straps 21a and 21b, respectively, onto the central underside portion of the dock platform structure symmetrically in respect to platform longitudinal centerline Φ . The details of connection to the platform and the means of coupling two or more such ballast tanks together may be similar in all respects to that described above in respect to pipes 13a and 13b, including the use of reinforcing members 20c and 20d.

The water level normally is at least no higher than the line indicated at 22 and may, under some circumstances, be even lower. Under such condition ballast tanks 19a and 19b are air-filled, and tanks 13a and 13b may be partially or wholly air- or water-filled to achieve desirable trim of the entire dock structure while supporting the vessel indicated at B. The buoyancy imparted to the dock structure by means of air-filled tanks 19a and 19b, and sometimes at least portions of 13a and 13b, would generally be insufficient to position and maintain the dock in its operable state as shown in the drawing. In order to accomplish this, additional positive buoyancy is provided by means of inflated rubber bags 22a and 22b positioned and secured between pipes 13a and 19a, and 13b and 19b, respectively. The inflatable bags may be fabricated of a suitable, flexible material such as rubber, polyethylene, or the like and are of a substantially watertight construction. Each of the inflatable bags is secured to the underside of the platform by means of flexible cables 23 passing through loops 24 and secured at their ends by means of eyes 26 fastened to the underside of crossbeams 12 so that the bags themselves are maintained in proper position under the dock when either in the inflated condition, as shown in the drawing, or deflated and hence in a relatively flat, flexible and loose condition. When the bags are in their inflated condition, additional buoyancy is provided to float the entire dry dock facility and vessel thereon. The displacement volume of bags 22a and 22b in their inflated condition, the volume of the air-filled portions of pipes 13a, 13b, 19a and 19b, and that portion of the dock platform under the surface of the water are selected to be at least equal to a volume of water whose weight is equal to the weight of the entire floating dock structure, including the pipes, inflatable bags, and necessary supportive and securing attachments, and the weight of the vessel and its various supportive equipment and personnel positioned on top of the dock platform.

After a vessel such as that indicated at B on the platform of the dock indicated at D in the drawing has been serviced and it is desirable to return the vessel to its ordinary attitude in the water, the dock may be submerged as follows:

Ballast tanks 19a and 19b are flooded with water by opening valves 27a and 27b in lines 28a and 28b respectively, fabricated of suitable stock material such as flexible polyethylene, rubber, or other suitable tubing. All valves referred to herein, such as the aforementioned ones, 27a and 27b, are accessible to the operator from the pier, dock or other convenient place of operation. All air and water lines referred to hereinafter are understood to be fabricated of similar suitable material and are long enough to service the dock in its submerged and floating position. Intake ends, 29a and 29b, of lines 28a and 28b, respectively, are positioned under the surface of the water; valves 27a and 27b are of a conventional type suitable for

the purpose and controlled by known means not further described or shown. Upon opening each of valves 27a and 27b water is admitted through lines 28a and 28b in the direction of arrows 31a and 31b and hence into each of the ballast tanks, 19a and 19b. Air is discharged from the ballast tanks by conventional relief means known in the art and not shown nor described herein. At the same time, valves 32a and 32b are opened; the latter valves are connected in lines 33a and 33b, respectively, in fluid communication by conventional fittings to inflatable bags 22a and 22b, respectively. Valves 34a and 34b, located in lines 36a and 36b, respectively, which provide fluid communication from tank 19a to inflatable bag 22a, and from tank 19b to 22b, respectively, are turned to the "off" position to isolate the inflatable bags pneumatically from the ballast tanks. As the ballast tanks take in water, and the buoyancy of the floating platform is reduced so that it sinks, air is forced from the inflated bags 22a and 22b to the atmosphere and the entire structure proceeds to submerge.

As mentioned earlier, tanks 13a and 13b may be incorporated as a part of my invention either in a sealed-off condition without fluid communicating means of any type, or as trimmer tanks in the manner as exemplified in the drawing. In such case, during submergence of the dock, valves 37a and 37b shown in lines 38a and 38b in fluid communication with tanks 13a and 13b, respectively, are also opened with tips 38c and 38d also below the surface of the water so that ballast may be taken in the direction of arrows 52a and 52b by these tanks, as necessary, to submerge the dock and to control the rate of descent. In addition, valves 37a and 37b, of a conventional type suitable for regulating fluid flow in their respective lines, may be regulated to control the attitude of the dock as it sinks. When used in this manner, and in any event during all periods of submergence, valves 39a and 39b, in pneumatic lines 41a and 41b, are turned to the "off" position to prevent water from going beyond the point of those valves for reasons that will be apparent hereinafter. Air discharge from tanks 13a and 13b during this period of operation is accomplished by conventional relief means known in the art.

After the dock has submerged to a desired depth, usually the bottom underneath the area where a vessel is to be serviced in dry dock, the hydrostatic pressure imposed on the system normally will have completely evacuated inflatable bags 22a and 22b to their flattened, deflated condition. Hence, my invention includes this novel expediency of using flexible buoyancy assistance bags which provide for reducing the buoyancy of the dock as it is submerged and less buoyancy is desired. By so doing, the entire operation during submergence is greatly increased in efficiency. More specifically, the expanded volume of the inflated bags required to float the dry dock is eliminated during submergence, when such buoyancy is not wanted, and the volume that such positive buoyancy tanks might have imposed upon the system is not present to require additional ballast during submergence.

Once the dock has submerged free from its supportive position in respect to the vessel indicated at B, the vessel may be moved away and the system is ready to accommodate another vessel.

When another vessel is to be serviced by the floating dry dock embodying my invention the following procedure is followed:

With the dock submerged in the manner as described above, the vessel to be serviced is maneuvered into position in the water over the dock. While this maneuvering is occurring, an air compressor such as the one indicated at 42 powered by motor 43 through appropriate linkage indicated at 44 is turned on to pressurize receiving tank 46. Valves 47a and 47b in pneumatic lines 48a and 48b, respectively, are opened to permit the flow of pressurized air in the direction of arrows 49a and 49b. Lines 48a

and 48b are in fluid communication with the capped ends of ballast tanks 19a and 19b, respectively, and the air admitted therethrough under pressure causes expulsion of the ballast water through lines 28a and 28b in the direction of arrows 51a and 51b through valves 27a and 27b, already opened during the submergence portion of the working cycle. Generally, all of the ballast may be expelled from tanks 19a and 19b without affecting the overall buoyancy of the system, or nearly so. If under given operating conditions, complete blowing of ballast from tanks 19a and 19b should tend to cause the dock to rise too far, the compressor action may be halted until the remainder of the ascent is desired. In the majority of cases, however, ballast tanks 19a and 19b may be completely evacuated of ballast water while the vessel overhead is still being maneuvered into position, and additional air pressure may be imparted into the ballast tanks for further ascent as will be explained.

Assuming that tanks 19a and 19b have been completely evacuated and additional air may be charged therein by the compressor working at a relatively reduced rate until it reaches its optimum pressure output level. At this point the compressor may be turned off. When the time is at hand to raise the dock further, evacuation valves 32a and 32b in lines 33a and 33b are closed; and valves 34a and 34b in lines 36a and 36b between tank 19a and bag 22a and tank 19b and bag 22b, respectively, are opened. The air under pressure in each of the ballast tanks 19a and 19b now flows through lines 36a and 36b in the direction of arrows 50a and 50b into bags 22a and 22b until equilibrium pressure is reached in both the ballast tanks and the inflatable bags which will be a function of the water depth and the external hydrostatic pressure head imposed through the flexible rubber bags. This will normally provide the dock with positive buoyancy which will cause the entire structure to commence or continue rising from below. Once positive buoyancy is imparted to the dock by means of the inflatable rubber bag, the dock will continue to rise at an increasing rate because of the decrease in hydrostatic force surrounding the inflatable bag and its ability to continue expanding due to its flexibility. In many instances such increased positive buoyancy as the dock continues to rise will be sufficient to support the vessel to be serviced out of the water along with associated equipment and personnel. If additional buoyancy is required, however, to raise the platform to its final operating position, the compressor is permitted to continue to charge bags 22a and 22b by imposing additional air under pressure into tanks 19a and 19b with which the bags are in fluid communication at this point. The platform then continues to rise until it emerges under the vessel to be lifted out of the water and supported for dry dock servicing.

When the dock is at or near reflootation, additional trim may be achieved by either admitting water into tanks 13a and 13b or expelling water therefrom by opening valves 39a and/or 39b and charging those tanks with compressed air thus expelling any water contained therein. If ballast is desired in these tanks, it is merely necessary to take in water through lines 38a and 38b by opening valves 37a and 37b; in such instance, water flows into tanks 13a and 13b in the direction of arrows 52a and 52b, respectively, while air is bled through conventional relief means (not shown) or, alternatively, through lines 41a and 41b in the direction of arrows 53a and 53b, respectively. When lines 41a and 41b are used to bleed air from tanks 13a and 13b, precaution should be exercised to prevent water from flooding into the receiving tank 46.

The operating cycle described above is now at its initial point as described first in the above specification. It is to be noted that due to the novel arrangement of my invention, a relatively small compressor may be used to refloat my dry dock compared to what would normally be necessary using older techniques where all of the ballast tanks are of a rigid construction. This is so because,

after a certain amount of initial evacuation of ballast by compressor action at a relatively high pressure (which will tend to drop if the dock begins to ascend) but at a nominal rate of displacement by the compressor, air may be transferred from the rigid ballast tanks to the flexible, inflatable bags without further work by the compressor itself. This causes the dock to rise away from the depth at which maximum compressor pressure is required, and a compressor with a relatively modest rating at the higher pressure may now continue at a higher rate of displacement but at a lower output pressure. This is to be contrasted to the situation where all of the ballast tanks are rigid and a greater amount of ballast water must be expelled at the relatively higher pressure existing at the outset of the ascension portion of the cycle. In my invention the additional water caused by having all of the ballast in rigid tanks is avoided to the degree that I accomplish maximum buoyancy by the use of the inflatable rubber bags. Moreover, I have the added advantage of being able to charge the inflatable rubber bags from the rigid ballast tanks, which are necessary to some degree, while my dry dock structure is rising from the bottom. Thus using my novel invention a dock may be raised relatively rapidly with a smaller compressor than would normally be required using all rigid ballast tanks, and the dock may be submerged more rapidly by virtue of the deflatable rubber bags when that portion of the cycle is effectuated.

As noted briefly above, the structure shown in the drawing merely exemplifies one form of my invention and serves to illustrate the modular nature of my novel device. For example, almost any length of dock may be accommodated by merely coupling additional structural sections and ballast pipes in the manner described in some detail at the outset of this specification. In addition it should be noted that the inflatable rubber bags 22a and 22b are shown as a series of individual bags linked together at the connection indicated at 54. Although not shown it is understood that this coupling also provides conventional means for fluid communication between the bags 22b, and, although mostly hidden by the dock platform structure, the same applies to bags 22a shown in the drawing.

To give my dry dock arrangement added stability, a pair of spuds or pipe guides 56a and 56b may be employed, each one slidably secured by means of guides 57a and 57b to each side of the dock. The bottom of the spuds (not shown) are suitably secured to the bottom. Toward the top of each spud a series of holes 58 may be drilled. While the dock is being raised, the spuds and their sliding guide tend to maintain the dock in proper trim; once the dock is refloated, pin 59 may be placed in the hole nearest the underside of guide 57b (and 57a on the other side although not shown) to hold the dock in the raised position. Other suitable securing means may be used, and once the dock is thus secured all fluid lines may be closed so that the compressor unit and flexible lines may be disconnected for use elsewhere.

Although the foregoing specification is in some detail, it is understood that this is done for purposes of illustration and is not intended to impose unnecessary limitations on my invention which may be practiced in numerous versions within the spirit thereof and scope of the appended claims.

What is claimed is:

1. In a submersible dock to lift and support a vessel out of water, said dock having a rigid hollow ballast compartment secured to the underside thereof, first means to convey water into and out of said compartment, and second means in fluid communication with the atmosphere and said compartment to pump air into the compartment and expel water contained therein through said first means, the improvement comprising, in combination: an inflatable bag collapsible to a deflated condition; fastener means to secure said bag in the inflated and deflated condi-

tion to the underside of said dock; valve means connected in fluid communication with said bag to expel air therefrom when said dock is being submerged and block air from being expelled when the dock is being refloated and floating; and means in fluid communication with the atmosphere and said inflatable bag to pump air into said bag and expand the bag to its inflated condition, said inflated bag, ballast compartment and water displacing portions of said dock being selected to have a combined volume at least as great as a volume of water having a weight equal to said dock, including said rigid ballast compartment and bag, and the vessel supported thereon; whereby said dock may be submerged and the inflatable bag deflated when water is conveyed by said first means into said ballast compartment, and refloated to lift and support a vessel thereon when the water is expelled from said ballast compartment by said second means and the inflatable bag is filled with air by said means in fluid communication with the atmosphere and the inflatable bag.

2. A submersible floating dock to lift and support a vessel out of water, comprising in combination; a platform; at least two segments of enclosed hollow pipe in spaced apart relationship to each other and secured to the underside of said platform; a pneumatically inflatable bag collapsible to a deflated condition when said dock is submerged below the surface of the water; means connected in fluid communication with said inflatable bag to convey air therefrom when said dock is being submerged and block air from being conveyed therefrom when the dock is being refloated and floating; means to secure said bag in the inflated and deflated condition on the underside of said platform; first means in fluid communication with the water in which said floating dock operates and said pipe segments to convey water into and out of the pipes, said dock being imparted with negative buoyancy when water is conveyed into and fills said pipe segments; a source of compressed air; means in fluid communication with said pipe segments and said source of compressed air to pump air into said pipe segments and expel the water contained therein through said first means; and means in fluid communication with said pipe segments into the inflatable bag after the pipe segments are filled with air, the combined volume of said pneumatically inflatable bag in the inflated condition, the portions of said pipe segments filled with air and the water displacing portion of said dock platform when floating, being at least as great as a volume of water having a weight equal to the entire dock structure and the vessel supported thereon, whereby said dock with a vessel supported thereon is caused to have positive buoyancy when said pipe segments are filled with air and said pneumatically inflatable bag is in the inflated condition.

3. A submersible floating dock to lift and support a vessel out of the water, comprising in combination: a platform; a plurality of parallel, enclosed, hollow pipes secured to the underside of said platform, one of said pipes located along a first lower edge of said platform, another of the pipes located along the lower edge of the platform opposite to said first lower edge, and at least one other of said pipes located under the center portion of the platform; first and second pneumatically inflatable bags collapsible to a deflated condition; means to secure said bags in the inflated and deflated condition on opposite sides of said platform equidistant from the center of the platform and immediately adjacent to the underside thereof; means connected in fluid communication with each of said bags to expel air therefrom when said dock is being submerged and block air from being expelled when the dock is being refloated and floating; first means in fluid communication with the water in which said floating dock operates and preselected ones of said hollow pipes under the center portion of the platform to convey water into and out of the preselected pipes, said preselected pipes having an internal volume sufficient to cause the dock structure to have a negative buoyancy

when the preselected pipes are filled with water; a source of compressed air; means in fluid communication with said preselected hollow pipes and said source of compressed air to convey air under pressure into the preselected hollow pipes and expel water contained therein through said first means; and means in fluid communication with said preselected hollow pipes and said inflatable bags to convey air from the preselected hollow pipes into the inflatable bags after the preselected hollow pipes are filled with air, the combined volume of said pneumatically inflatable bags in the inflated condition, the portions of said preselected pipe segments filled with air, and the water displacing portion of said dock platform when floating being at least as great as a volume of water having a weight equal to the entire dock structure and the vessel supported thereon.

4. The floating dock in accordance with claim 3 and wherein further said preselected ones of said hollow pipes also include said pipes located along the first lower edge of said platform and the lower edge of the platform opposite to said first lower edge.

5. In a submergible dock to lift and support a vessel out of water, said dock having at least two rigid ballast tanks secured to the underside thereof, first means to convey water into and out of said tanks, and second means in fluid communication with the atmosphere and said tanks to pump air into the tanks and expel water contained therein through said first means, the improvement comprising, in combination: an inflatable bag collapsible to a deflated condition; means to secure said bag in the inflated and deflated condition to the underside of said dock between said ballast tanks; means connected in fluid communication with said bag to expel air therefrom when said dock is being submerged and block air from being expelled when the dock is being refloated and floating; means in fluid communication with the atmosphere and said inflatable bag to pump air into said bag and expand the bag to its inflated condition, said inflated bag, ballast tanks, and water displacing portions of said dock being selected to have a combined volume at least as great as a volume of water having a weight equal to said dock, including said tanks and bag, and the vessel supported thereon; whereby said dock may be submerged and the inflatable bag deflated when water is conveyed by said first means into said ballast tanks, and refloated to lift and support a vessel thereon when the water is expelled from said ballast tanks by said second means and the inflatable bag is filled with air by said means in fluid communication with the atmosphere and the inflatable bag; first and second vertical pipes secured to the ground surface under the water in which said dock operates, said first pipe aligned in tangential contact with one side of said platform and said second pipe aligned in tangential contact with the other side of the platform; means secured to each side of said dock and in sliding contact around at least a portion of each of said vertical pipes to restrain the pipes in tangential and sliding contact with the sides of the dock; and means to secure said dock to said vertical pipes and prevent relative motion of the dock in respect to the vertical pipes when the dock is in floating position.

6. A submergible floating dock to lift and support a vessel out of water, comprising in combination: a platform; a rigid hollow ballast compartment secured to the

underside of said platform; a pneumatically inflatable bag collapsible to a deflated condition when said dock is submerged below the surface of the water; means connected in fluid communication with said inflatable bag to convey air therefrom when said dock is being submerged and block air from being conveyed therefrom when the dock is being refloated and floating; means to secure said bag in the inflated and deflated condition on the underside of said platform; first means in fluid communication with the water in which said floating dock operates and said ballast compartment to convey water into and out of the compartment, said dock being imparted with negative buoyancy when water is conveyed into and fills said compartment; a source of compressed air; means in fluid communication with said compartment and said source of compressed air to pump air into the compartment and expel the water contained therein through said first means; and means in fluid communication with said compartment and said inflatable bag to convey air from the compartment into the inflatable bag after the compartment is filled with air, the combined volume of said pneumatically inflatable bag in an inflated condition, the portions of said compartment filled with air and the water displacing portion of said dock platform being at least as great as a volume of water having a weight equal to at least the entire dock structure, whereby said dock is caused to have positive buoyancy when said compartment is filled with air and said pneumatically inflatable bag is in an inflated condition.

7. The submergible dry dock in accordance with claim 6 and wherein further the combined volume of said pneumatically inflatable bag in the inflated condition, the portions of said compartment filled with air and the water displacing portion of said dock platform when floating being at least as great as a volume of water having a weight equal to at least the entire dock structure and vessel with associated equipment and personnel to be supported thereon.

8. The method of submerging and refloating a dry dock operating on and in a body of water comprising the steps of: pumping water into a first zone within said dock when floating and simultaneously evacuating the air from and decreasing the water displacing volume of a second zone of said dock, said dock being caused to occupy a volume less than a volume of water having a weight equal to said entire dock structure, whereby said dock submerges in said body of water; and pumping air into said first zone within said dock when submerged until the water is evacuated therefrom, and then transferring air from said first zone to said second zone to increase the water displacing volume of the second zone until said dock is caused to occupy a volume greater than a volume of water having a weight equal to said entire dock structure, whereby said dock becomes positively buoyant and begins to rise to the surface of said body of water, and said second zone continues to increase in water displacing volume and accelerates the rise of said dock to the surface of the body of water.
